UNITED STATES PATENT OFFICE.

ERNEST COBURN, OF SPOKANE, WASHINGTON, ASSIGNOR TO THE HOLT MANUFACTURING COMPANY, OF STOCKTON, CALIFORNIA, A CORPORATION OF CALIFORNIA.

COMBINED HEADER AND THRASHER.

Application filed May 24, 1920. Serial No. 383,644.

To all whom it may concern:

Be it known that ERNEST COBURN, a citizen of the United States, residing in the city and county of Spokane and State of Washington, has invented new and useful Improvements in Combined Headers and Thrashers, of which the following is a specification.

This invention relates to combined headers and thrashers, wherein a header and thrasher are combined for operation in the field.

Combined harvesters adapted for side hill work frequently employ a machine wherein a single line of bearing wheels serve to support the thrasher and the inside of the header, the header being hinged to the thrasher and having its outer end supported by a grain wheel. An adjustable connection is formed between the header and thrasher for stabilizing the latter, and this serves as a leveling mechanism to maintain the thrasher upright when on a side hill. This single line of bearing wheels for the thrasher simplifies and facilitates the operation of leveling the thrasher, and in the present invention I make use of this same general scheme of supporting the thrasher on a single line of bearing wheels.

Heretofore in this type of support, the main supporting member for the thrasher has been placed between the thrasher frame approximately on a longitudinal central line thereof. This position of the main supporting member results in excessive side draft caused by the header which projects a considerable distance to one side of the main bearing wheel. Also it increases the weight on the outside header wheel and makes necessary a high elevation of the thrasher frame. This extra weight and side draft on the header causes the header wheel to dig in, and it has been found advisable in prior devices to positively drive this wheel by mechanism connected with the motor in the case of a self-propelled harvester, or otherwise in the case of drawn harvesters. A high thrasher frame such as results from necessity where the main bearing wheel is beneath the thrasher is a source of danger, especially in side hill work. Moreover, in transporting a combined harvester, it is necessary to reduce its width for traveling over ordinary roads since the length of the header frame varies from twelve to twenty-

four feet. Where two wheels were used to support the thrasher, one at each side, it has been the practice to disconnect the header frame at the point where it hinges on to the thrasher and transport the header on a separate truck. But this is not possible in prior single bearing line types of thrashers, since to remove the header would leave the thrasher approximately evenly balanced on the single line bearing members, and for stabilizing purposes an auxiliary wheel would have to be arranged on each side and such wheels are not always available. In one of the prior machines, of the type herein referred to, the header frame is merely shortened, allowing the grain wheel to be set inwardly toward the thrasher. This plan does not reduce the width as much as might be desired, and furthermore requires a special construction in the header frame.

In the present invention, I employ a single line of bearing or supporting members for the thrasher, the main bearing member being preferably of the endless track type. This track mechanism I arrange at the inside of the thrasher, thereby allowing the thrasher frame, if desired, to be dropped closer to the ground. A steering wheel is placed ahead of the track and in line therewith and the motor is so positioned that its weight is about evenly distributed on opposite sides of the single bearing line. Thus, so far as the thrasher is concerned, its weight is carried entirely on one side of the bearing line, and to overbalance it I hinge the header frame to the inside of the thrasher where its extreme length will be effective to prevent tipping of the thrasher. A grain wheel is used at the outer end of the header as in prior types of harvesters. Since the weight of the thrasher and header are in a sense balanced one against the other, there is no excessive weight thrown on the header frame, and hence there is no danger of the grain wheel on the outer end of the header sinking into the ground. Also since the main bearing member for the harvester is closer to the header, the objectionable side draft hereinbefore referred to is overcome, and the necessity for positively driving the grain wheel is eliminated. Moreover, the header frame is disconnectible where it hinges on to the main frame, and when removed, its

grain wheel can be transferred to the opposite side of the thrasher to support the latter. The header frame, reel and screen, are made collapsible and they may be folded up 5 and thrown in any convenient place on the thrasher for transporting.

Referring to the accompanying drawings:

Fig. 1 shows a side elevation of a harvester embodying my invention.

10 Fig. 2 shows a perspective view of the same with the parts in position for transport.

Fig. 3 shows a rear elevation of the harvester in operating position.

15 Fig. 4 shows a detail view in section of the collapsible reel.

In the present form of my invention, I show a truck frame 10 on one side of which is carried the thrasher 11 and on the other 20 side a header 12 is connected by means of hinges 13. A single main load carrying member 14 is arranged at the rear of the truck frame, being shown as a chain track truck mechanism, although it may obviously 25 be a round wheel. At the front of the truck frame and in line with the track is a steering wheel 15. The motor 16 is positioned on the truck frame at the front thereof and its weight is approximately balanced there- 30 on. A grain wheel 17 is journaled on the outer end of the header frame and supports the latter. For stabilizing the thrasher, a leveling arm 18 pivoted to the header frame extends up to the thrasher where a toothed 35 rack 19 on the end of the leveling arm engages with the pinion 20 which through worm gearing 21 is operated in either direction to vary the inclination of the thrasher relative to the header whereby to accommodate 40 the machine to side hill conditions. The worm gearing will hold the pinion against turning, and hence the header frame and thrasher will be kept in proper position. A more detailed description of this stabilizing 45 feature will be found in my companion application Serial No. 383,643, filed May 24, 1920.

All of the weight of the thrasher is to one side of the main bearing member and all the 50 weight of the header is to the opposite side thereof. The thrasher, even though heavier, has less leverage than the header, and consequently the latter is effective to overbalance the weight of the thrasher at all times. Furthermore, the leveling mechanism insures 55 that the thrasher will always be kept in upright position when the machine is on side hill, therefore there is no danger of tipping over. The header frame is disconnectible 60 from the truck frame by removing the hinge pins of the hinges 13 where it connects thereto, and when removed, its wheel can be transferred to the outside thrasher frame. For this purpose, axle 17^a of the wheel is 65 carried removably in bearings on the header

frame and the thrasher frame is provided with bearings 17^b to receive said axle. Bearings 17^b are quite similar to those provided on the header frame for said axle. The header is provided with a reel 22 having radial arms 23, hinged to spiders 24 whereby said arms may be folded and the reel when collapsed may be placed on top of the thrasher for transporting. Two diametrically opposite arms are rigid and the remaining arms are held in extended position by links 23^a. Also the header is provided with a screen 34 which is hinged at 25 to the header frame. This screen is normally locked in upright position, but when the header frame is to be transported, the screen can be folded against the header frame for greater compactness. The folded screen and header may then be disposed along the outside of the thrasher resting on the axle 17^a of the grain wheel. Thus, a very narrow machine is produced for transporting along narrow roads and no separate transport trucks are required for taking care of the header.

The position of the track mechanism at the side of the thrasher makes possible a lowering of the separator frame, and it may be seen that the bottom of the separator is below the top of the chain track. To insure proper clearance between the ground and the bottom of the thrasher, I relocate the main separator fan 26 which ordinarily is carried below the thrasher. In the present case, I arrange it in front of the thrasher with its shaft 27 in line with, and connected directly to, the crank shaft of the motor. The fan has an elongated and shallow throat 28 extending rearwardly and beneath the thrasher to a point where its blast will be directed upon the grain carrier.

Various changes in the construction and arrangement of the several parts herein shown and described may be employed without departing from the spirit of my invention as disclosed in the appended claims.

Having thus described my invention, what I claim and desire to secure by Letters Patent is:

1. In a combined header and thrasher, a thrasher, a header connected to one side thereof and having a supporting wheel at the outer end and a single line of bearing members for the thrasher and inner end of the header positioned between the thrasher and header, the weight of the header being effective to prevent the thrasher from tipping.

2. In a combined header and thrasher, a thrasher, a header connected to one side thereof and having a supporting wheel at the outer end and a single line of bearing members for the thrasher and inner end of the header positioned between the thrasher and header, the weight of the header being

effective to prevent the thrasher from tipping, said header being disconnectible from the thrasher and its wheel being removable and transferable to the outside of the 5 thrasher for transporting the latter.

3. In a combined header and thrasher, a truck frame having a single line of bearing members, a thrasher carried at one side of the truck frame, a header carried at the 10 opposite side, said header having a supporting wheel at its outer end.

4. In a combined header and thrasher, a truck frame having a single line of bearing members, a thrasher carried at one side of the truck frame, a header carried at the opposite side, said header having a supporting wheel at its outer end, said header being also hingedly connected to the truck frame, and an adjustable stabilizing connection between 20 the header and thrasher for maintaining the thrasher upright when the header is on an incline.

5. In a combined header and thrasher, a truck frame having a single line of bearing 25 members, a thrasher carried at one side of the truck frame, a header carried at the opposite side, said header having a supporting wheel at its outer end, the header being disconnectible from the truck frame and its 30 wheel being removable and transferable to the opposite side of the thrasher for supporting the latter during transport.

6. In a combined header and thrasher, a thrasher, a header connected to one side 35 thereof and having a supporting wheel at the outer end and a single line of bearing members for the thrasher and inner end of the header positioned between the thrasher and header, the weight of the header being 40 effective to prevent the thrasher from tipping, said header being disconnectible from the thrasher and its wheel being removable and transferable to the outside of the thrasher for transporting the latter, and a 45 removable reel included in the header comprising spiders and radial arms hinged thereon to the forward end, whereby the reel may be stored on top of the thrasher.

7. In a combined header and thrasher, a 50 thrasher, a header connected to one side thereof and having a supporting wheel at the outer end and a single line of bearing members for the thrasher and inner end of the header positioned between the thrasher and header, the weight of the header being 55 effective to prevent the thrasher from tipping, said header being disconnectible from the thrasher and its wheel being removable and transferable to the outside of the 60 thrasher for transporting the latter, an up-

right screen included in the header hinged to the header frame and foldable thereagainst for compactness whereby the header frame may be carried on the thrasher when the latter is in transport position.

65

8. In a combined header and thrasher, a thrasher, a header connected to one side thereof and having a supporting wheel at the outer end and a single line of bearing members for the thrasher and inner end of the header positioned between the thrasher and header, the weight of the header being 70 effective to prevent the thrasher from tipping, said header being disconnectible from the thrasher and its wheel being removable 75 and transferable to the outside of the thrasher for transporting the latter, a fan included in the thrasher arranged at the front end thereof and having a throat extending rearwardly at the bottom of the 80 thrasher.

75

9. In a combined header and thrasher, a thrasher, a header connected to one side thereof and having a supporting wheel at the outer end and a single line of bearing 85 members for the thrasher and inner end of the header positioned between the thrasher and header, the weight of the header being effective to prevent the thrasher from tipping, said header being disconnectible from 90 the thrasher and its wheel being removable and transferable to the outside of the thrasher for transporting the latter, a fan included in the thrasher arranged at the front end thereof and having a throat extending rearwardly at the bottom of the 95 thrasher, and a motor for operating the thrasher and header mechanism arranged at the front of the harvester and having its crank shaft in line with, and connected to, 100 the shaft of the thrasher fan.

95

10. In a combined header and thrasher, a thrasher having a fan arranged at the forward end thereof and an elongated and shallow throat for the fan extending rearwardly of the thrasher and beneath the same to a point where its blast may be directed upon the grain carrier, and a motor on said combined header and thrasher for operating the thrasher and header mechanism, said 105 motor having its crank shaft arranged in line with the shaft of the thrasher fan and connected directly thereto.

105

In testimony whereof I have hereunto set my hand in the presence of two subscribing 110 witnesses.
